UNITED STATES PATENT OFFICE

91,651

DESIGN FOR A DEODORANT CONTAINER

Charles D. Farmer, Detroit, Mich.

Application December 11, 1933, Serial No. 50,030

Term of patent 14 years

To all whom it may concern:

Be it known that I, CHARLES D. FARMER, a citizen of the United States, residing at Detroit, in the county of Wayne and State of Michigan, have invented a new, original, and ornamental

Design for Deodorant Containers, of which the following is a specification, reference being had to the accompanying drawing, forming a part thereof:

The figure is a perspective view of a deodorant container, showing my new design.

I claim:

The ornamental design for a deodorant container, as shown.

CHAS. D. FARMER.
